DESIGN FOR A WATCHCASE COVER

Leslie Saks, New York, N. Y.

Application May 1, 1945, Serial No. 119,327

Term of patent 3½ years

(Cl. D42—8)

To all whom it may concern:

Be it known that I, Leslie Saks, a citizen of the United States, residing at New York, in the county of New York and State of New York, have invented a new, original, and ornamental Design for a Watchcase Cover, of which the following is a specification, reference being had to the accompanying drawing, forming a part thereof.

In the drawing:

Fig. 1 is a plan view of a watchcase cover showing my new design;

Fig. 2 is a transverse side view thereof;

Fig. 3 is a longitudinal side view of the same; Fig. 4 is a sectional view, the section being taken on the line 4—4 of Fig. 1.

The sides not shown are identical with the one shown, and the bottom is plain. The letter "A" shown in broken lines is merely representative of any letter of the alphabet.

I claim:

The ornamental design for a watchcase cover, as shown and described.

LESLIE SAKS.
